LACE OR SIMILAR ARTICLE

Bert Edson, Pawtucket, R. I.

Application November 18, 1952, Serial No. 22,357

Term of patent 3½ years

(Cl. D47—6)

To all whom it may concern:

Be it known that I, Bert Edson, a citizen of the United States of America, residing in Pawtucket, county of Providence, and State of Rhode Island, have invented a new, original, and ornamental Design for a Lace or Similar Article, of which the following is a specification, reference being had to the accompanying drawing, forming part thereof, wherein the figure is a plan view of a piece of lace, showing my new design on a dark background, so as to bring out more clearly the details thereof, a unit of which is contained within the dot and dash lines.

I claim:

The ornamental design for a lace or similar article, substantially as shown and described.

BERT EDSON.
